UNITED STATES PATENT OFFICE.

JAMES B. VERNON, OF PITTSBURGH, PENNSYLVANIA.

COMPRESSION AND SUCTION DEVICE.

1,210,730.

Specification of Letters Patent. Patented Jan. 2, 1917.

Application filed December 29, 1913. Serial No. 809,381.

To all whom it may concern:

Be it known that I, JAMES B. VERNON, resident of Pittsburgh, in the county of Allegheny and State of Pennsylvania, have 5 invented a new and useful Improvement in Compression and Suction Devices, of which the following is a specification.

This invention relates to apparatus for producing suction or compression, or rotary 10 pumps, and particularly to that class of pumps embodying a chamber in which is eccentrically mounted a rotary hub or piston carrying a number of movable blades which sweep around a crescent shaped space 15 between the piston and outer casing and force the fluid therethrough.

The object of the invention is to produce a pump of the type described, which has 20 high efficiency and produces a maximum continuous or uninterrupted suction or compression effect, and in which the induction and eduction ports may be of large area, and are so arranged as to prevent wear 25 of the piston blades.

25 A further object of the invention is to produce a pump provided with simple and effective means for circulating a liquid therethrough, so as to produce a tight seal between all relatively movable surfaces and 30 lubricate all the moving parts within the pump, and which thereby increases the efficiency.

35 Further objects of the invention are in part obvious and in part will appear more in detail hereinafter.

In the drawings Figure 1 represents a front perspective view of a pump embodying the invention, the front casing head and rotor being omitted; Fig. 2 is a longitudinal 40 sectional view on the line 2—2 Fig. 1, and showing the front end head and rotor, and with the lower half of the rotor in side elevation; Fig. 3 is a sectional elevation on the line 3—3, Fig. 2 looking in the direction 45 of the arrows; and Fig. 4 is a detail perspective view of one of the piston blades.

Referring to the drawings, which illustrate one of many forms of the invention, 1 indicates a suitable casing having therein a 50 cylindrical bore or chamber closed at its ends by the heads 2 and 3. One of the end heads may be integral with the cylindrical portion or side wall of the casing, but in the form shown, both of said heads are separate and are clamped to the end faces of the 55 cylindrical portion by tap screws or bolts 4.

The rotor comprises a hub or piston 5, which has a large cylindrical portion fitting snugly between the end heads of the casing, and which at one side, as at 60 6, bears against the side casing wall. This hub or piston is provided with a plurality of circumferentially spaced radial slots or sockets 7, three being shown, in each of which is mounted a movable 65 piston blade. Said blades may be of any type, but preferably are of the form and arrangement shown in the application for compression and suction device, filed jointly by me and Martin J. Sieffert, of even date 70 herewith, Serial No. 809,412. Each blade is pressed yieldingly outward against the side casing wall by one or more springs 8, as shown in Fig. 2, said springs bearing at 75 their inner ends against the bottoms of the slots 7 and having their outer ends lying in notches 9 in the inner edges of the piston blades. These springs allow the blades to move radially in the slots 7 as they travel around the crescent shaped chamber 10, between the piston and the side casing wall. The piston may be rotated in any suitable manner and as shown is provided with end journal portions 11 extending into bearings 80 in the heads of the casing. One of said journals is extended beyond its bearing for connection to the power driving means, and is shown as provided with fast and loose pulleys 12 and 13 for a driving belt. The particular arrangement of the driving means 85 is not essential.

The pump so far described is of the same general type and construction as that shown in the prior Patent No. 1,018,221, granted 90 jointly to me and George De Camp, February 20th, 1912. In the patented structure the induction and eduction ports were located in one of the end heads of the casing and communicated with grooves on the inner surfaces of the head, which grooves extended in both directions from said ports circumferentially of the compression chamber for producing a continuous and uninterrupted flow of fluid and equalizing the pressures on the opposite sides of the piston 100 blades. These elongated grooves were located at narrow ends of the crescent shaped chamber, and, since they were located in the end heads, could not be wider than said chamber. According to the present invention I locate the induction and eduction 105 ports in the cylindrical portion or side wall 110

of the casing, so they can be made of any desired size or area and can be extended as close to the ends of the crescent shaped chamber as desired.

5 As shown in the drawings the lower portion of the casing is enlarged and cored out to form an induction chamber 14 and an eduction chamber 15. These chambers are provided with suitable connections 16 and 17, which respectively lead to any suitable place where it is desired to produce suction or compression. The induction chamber 14 communicates with the crescent shaped chamber 10 through a plurality of ports 18, 15 which are shown as elongated slots or openings inclined to each other circumferentially of the casing wall and also inclined to a plane normal to the pump axis, and arranged in the form of two diamonds as 20 shown in Fig. 1. Eduction chamber 15 communicates with the crescent shaped chamber 10 through a plurality of ports 19, shown as elongated slots or openings arranged in the same manner as the openings 18 and for 25 the same reason. By inclining the slots or openings the movable piston blades pass over said openings gradually and contact with the edges thereof progressively from end to end. With this arrangement there are 30 no sharp edges lying directly crosswise of the movement of the piston blades to suddenly impinge thereagainst and wear them out.

The casing and rotary hub or piston may 35 be made of any suitable length, so that there is plenty of room in the side wall of the casing for the ports or openings, and each port may be made of any desired area by using the proper number and arrangement 40 of openings, that shown being merely illustrative.

The lower ends of the openings 18 and 19 lie close to the ends of the chamber 10, and said openings extend for some distance away 45 from both ends of said chamber. They form by-passes around the pistons as they approach and recede from the ends of the chamber, and prevent the flow of fluid into and out of said chamber from being interrupted, pulsating, or intermittent, and also 50 equalize the pressures on the opposite sides of the pistons as they travel past the ports and to and from the ends of the chamber. This prevents back pressure or suction on 55 the piston blades and produces a steady and uninterrupted flow of liquid through the pump thereby increasing its efficiency. By using a sufficient number of openings for the induction and eduction ports, and by 60 properly arranging them in the casing wall, a maximum and uniform suction and compression effect may be produced without incurring the liability of unduly wearing out the piston blades in passing said ports. In 65 order to further increase efficiency, means is

also provided for circulating through the pump a continuous stream of liquid, which may be glycerin or some similar material, but is preferably an oil and thereby serves as a lubricant. As shown in the drawings 70 eduction chamber 15 is provided with an outlet 20 at its lowest point, from which a suitable conduit or pipe, indicated at 21, leads to an inlet 22 at or near the top of the induction chamber 14. Said conduit may 75 be provided with any suitable form of regulating valve 23 for controlling the flow of liquid through the pump, although this is not essential.

In use of the apparatus a quantity of liquid, such as oil, is poured into the chamber 15. Rotation of the hub or piston produces a suction effect in chamber 14 and a compression effect in chamber 15. The oil is forced out of chamber 15 and flows through 80 the conduit 21 into the chamber 14, from which it is carried with the inflowing air into the crescent shaped chamber 10. It penetrates into the crevices of the moving parts and lubricates all the moving surfaces 85 thereof, and also fills all spaces between the piston blades and cylinder walls and effectively seals the same thereby preventing 90 escape of air around the piston blades.

The machine described may be used for 95 various purposes, and either for its suction or for its compression effect. It can be used for dental purposes or for cleaning, in which cases the suction effect is most useful, but it is also adapted for producing compression 100 for operating blow-pipes or like devices. It is of large capacity for its size, is very effective and produces a continuous and uninterrupted flow of fluid. It is self lubricating so that it will run steadily and continuously or 105 may be operated intermittently over long periods of time without attention on the part of the operator, so that it is particularly adapted for use by unskilled operators or in places where it is either unlikely to receive 110 attention or is more or less inaccessible. It will therefore stand considerable neglect or even hard or rough usage without material loss of efficiency.

What I claim is:

1. A machine of the character described, comprising a casing provided with a chamber, a rotor eccentrically located in said chamber, piston blades movably mounted in said rotor and held with their free edges in 115 contact with the walls of said chamber, the side wall of the casing being provided with induction and eduction ports, each of said ports comprising a plurality of elongated slots inclined to a plane normal to the rotor axis and converging in both directions circumferentially of the casing toward the ends 120 of said ports.

2. A machine of the character described, comprising a casing provided with a pump 125

chamber and side induction and eduction chambers, and a wall separating said pump chamber from said side chambers, a rotor eccentrically located in said pump chamber,
5 piston blades movably mounted in said rotor and held with their free edges in contact with the wall of said pump chamber, said separating wall being provided with induction and eduction ports, each comprising a plurality
10 of elongated slots or openings lying at an incline to a plane normal to the rotor axis, some of said slots diverging from and others

converging toward each other circumferentially of the casing, said ports extending from end to end of the induction and eduction chambers and being wider intermediate the ends than at the end thereof. 15

In testimony whereof, I have hereunto set my hand.

JAMES B. VERNON.
